UNITED STATES PATENT OFFICE.

ALEXANDER E. WISE, OF NEW YORK, N. Y.

GARMENT-MARKING DEVICE.

No. 870,209.

Specification of Letters Patent.

Patented Nov. 5, 1907.

Application filed June 7, 1906. Serial No. 320,530.

To all whom it may concern:

Be it known that I, ALEXANDER E. WISE, a citizen of the United States, residing in the borough of Manhattan, city, county, and State of New York, have invented 5 certain new and useful Improvements in Garment-Marking Devices, of which the following is a specification.

My invention relates to appliances used in connection with the fitting of garments to the person of the 10 wearers for the purpose of marking the garments horizontally to indicate the proper line of trim or severance, particularly for ascertaining and regulating the length and natural hang of skirts, and the like.

The object is to insure greater convenience, rapidity 15 and accuracy in the marking of garments than has heretofore been attained,—the distinguishing feature of the invention consisting in the use of a curved horizontal tube or conduit the inner concave side of which is constructed in such manner that marking powder may, by 20 suitable means, be ejected horizontally through said concave side of the conduit substantially as herein set forth.

My device is designed particularly and only for the 25 marking of garments on horizontal lines, without direct handling or contact therewith; and the invention consists essentially in the construction and arrangement of parts hereinafter described and claimed specifically.

In the accompanying drawings, Figure 1, is a top view of my appliance arranged for use; Fig. 2, a side 30 elevation illustrating the use thereof; Fig. 3, is a horizontal section upon a larger scale of my horizontal marker; Fig. 4, a sectional detail of a preferred form of bulb nozzle.

The marker 1, consists of a curved tube or conduit 35 preferably of semi-circular form or approximately so, in the inner convex surface of which are a series of holes 2. The marker 1, may be formed of a section of pipe bent to the required form and formed with the perforations 2, or it may be otherwise made in any desired manner, 40 the essential feature being the series of horizontal holes 2. The marker 1 is supported adjustably upon a suitable stand by any desired mechanical expedient. Thus, by way of illustration in the drawings, the marker 1, is formed on its convex side with a sleeve 3, fitting 45 over a vertical rod 4 and held adjustably thereon by a set screw 5,—the rod 4, projecting upward from a suitable base or support 6, although the vertical adjustment of the marker 1, may obviously be provided for by other means if desired, with like results. One end of the 50 marking tube 1, is closed as by a plug or cap 7, the other end being open and adapted to have applied to it one end of a flexible tube 8, to the other end of which is attached the nozzle 9 of a compressible bulb 10 of any desired form and construction. The function of 55 the bulb is to force powdered chalk or other suitable material reduced to an impalpable condition into the

marking tube 1, and through the holes 2. The powder may be placed directly within the compressible bulb 10, as I have found to be entirely practicable, or otherwise so disposed that the compression of the bulb will 60 cause the injection of the powder into the marking tube 1.

The vertical rod 4 is formed with a scale 11, preferably in inches and fractions thereof by means of which the marker 1 may be definitely set to a prescribed vertical position.

12 is a platform on which the person to be fitted may stand, although this feature forms no part of my invention.

The use of my improved marking device will be 70 readily understood. Take for instance a skirt the bottom of which has to be cut or trimmed to render the edge true and of uniform height above the ground. The device being placed in proper position with relation to the wearer of the skirt, the marker is simply 75 set vertically to the desired level and the bulb 10 compressed, ejecting through the semicircular row of holes 2 fine jets of powder which impinge upon the skirt in a true horizontal plane creating a well defined line of severance. The person still maintaining the same position, the device is moved to another position with relation to the person and the bulb 10 again pressed forming a continuation of the horizontal line first 80 formed and this is repeated as often as is necessary to complete the circuit. Ordinarily two or three changes 85 in position are sufficient to properly mark the garment. By thus marking the garment without touching it by hand I attain important advantages. Where garments are marked by hand as heretofore the operation is not only difficult and laborious, but it is also more or less 90 inaccurate, the handling of the garment necessarily disturbing it more or less and altering the relation of one part to another, whereas by causing the jets of marking powder to impinge simultaneously upon the opposed surface of the garment a true horizontal line 95 is attained unaffected by the folds, and not impaired by any disturbance of the garment. Not only am I enabled to thus conveniently attain greater accuracy in marking a garment, but the whole operation may be performed in a small fraction of the time requisite to 100 mark the garment by hand.

What I claim as my invention and desire to secure by Letters Patent is,

1. In a garment marking device of the character designated, the combination of a curved conduit the concave surface of which is perforated longitudinally and horizontally, means for adjusting said conduit vertically upon its support, said support, and means for injecting a marking powder into said curved conduit and ejecting said powder therefrom through the concave side thereof, for the purpose described.

2. In a garment marking device of the character designated, the combination of a curved conduit formed with a horizontal series of holes in its concave side, a vertical sup-

- port for said conduit, adjustable means for securing said conduit to said vertical support, and means for injecting a marking powder into said conduit and ejecting the same therefrom through said horizontal series of holes, for the 5 purpose described.
3. In a garment marking device of the character designated, the combination of a curved conduit formed with a horizontal series of holes in its concave side, a support for said conduit consisting of a standard formed with a vertical scale indicating different heights, adjustable means for securing said conduit on said standard and with relation to said vertical scale, and means for injecting a marking powder into said conduit and ejecting the same therefrom through said horizontal series of holes, for the purpose described. 10
4. In a garment marking device of the character designated, the combination of a horizontal semi-circular marking tube the concave side of which is perforated longitudinally and horizontally, adjustable means for securing said tube upon a vertical support, said vertical support, and means for injecting a marking powder into said semi-circular marking tube and ejecting said powder therefrom through the concave side thereof, for the purpose described. 15
5. In a garment marking device of the character designated, the combination of a curved conduit the concave side of which is perforated horizontally and longitudinally, a flexible tube connecting with said curved conduit, and means for injecting a marking powder through said flexible tube into said curved conduit and ejecting the powder therefrom through the perforated concave side thereof, for the purpose described. 20
6. In a garment marking device of the character designated, the combination of a curved conduit the concave side of which is perforated horizontally and longitudinally, adjustable means for securing said curved conduit to a vertical support, said vertical support, a flexible tube connecting with said curved conduit, and means for injecting a marking powder through said flexible tube into said curved conduit and ejecting the powder therefrom through the perforated concave side thereof, for the purpose described. 25
7. In a garment marking device of the character designated, the combination of a vertical standard, a curved horizontal marking tube formed with a series of holes in its concave side, adjustable means for securing said mark- 30
- ing tube upon said vertical standard, means for closing one end of said horizontal marking tube, a flexible tube connecting with the otherwise open end of said horizontal marking tube, said flexible tube, and means for injecting a marking powder through said flexible tube into said horizontal marking tube and ejecting the same therefrom through said series of holes in the concave side thereof, for the purpose described. 35
8. In a garment marking device of the character designated, the combination of a supporting standard formed with a vertical scale indicating different heights, a curved horizontal marking tube formed with a series of holes in its concave side, adjustable means for securing said marking tube upon said supporting standard and with relation to the vertical scale thereon, means for closing one end of said horizontal marking tube, a flexible tube connecting with the otherwise open end of said horizontal marking tube, said flexible tube, and means for injecting a marking powder through said flexible tube into said horizontal marking tube and ejecting the same therefrom through said series of holes in the concave side thereof, for the purpose described. 40
9. A skirt marker composed of a base, a rod projecting upwardly therefrom, a slide movable upon the rod, means for clamping the slide to the rod at different elevations, a perforated tube carried by the slide, and means for ejecting a marking powder from said tube, substantially as specified. 45
10. A skirt marker composed of a base, a rod projecting upwardly therefrom, a slide movable upon the rod, means for clamping the slide to the rod at different elevations, a curved perforated tube carried by the slide, and a powder gun communicating with the tube, substantially as specified. 50
11. In a garment marking device of the character designated, the combination of a curved conduit open longitudinally on its concave side in horizontal line, adjustable means for securing said curved conduit to a vertical support, said vertical support, and means for injecting a marking powder into and ejecting it through the open concave side of said curved conduit, for the purpose described. 55
